UNITED STATES PATENT OFFICE.

JOHN EFFEIER, OF SPRINGFIELD, OHIO, ASSIGNOR OF ONE-THIRD TO SPENCER W. WARING, OF SPRINGFIELD, OHIO.

ELECTRIC SWITCH.

Application filed June 7, 1926. Serial No. 114,043.

My invention relates to improvements in electric switches, it more particularly relating to a switch which is thermostatically controlled.

5 The object of my invention is to provide simple and effective devices for opening and closing electric switches by mechanism which is controlled by a thermostat.

A further object of the invention is to 10 provide a switch operating mechanism of the character described which can be adjusted to a nicety so that the mechanism will be responsive to but slight changes in temperature if desired; the adjustment being 15 such, however, that the mechanism can be regulated to operate upon wider ranges of temperature.

In the accompanying drawings:

Fig. 1 is a top plan view of a mechanism 20 embodying the improvements.

Fig. 2 is a side elevation of the same showing the switch in closed position.

Fig. 3 is a section on the line 3—3 of Fig. 1.

25 Fig. 4 is a side elevation showing the switch in open position.

Fig. 5 is a section on the line 5—5 of Fig. 2.

Referring to the drawings, 1 represents 30 a supporting base for the mechanism. Mounted on this base is a motor, shown in the present case as a spring motor, 2 and 2' representing upright supports, 3 an arbor suitably mounted in the supports, 4 a coil spring having one end connected to the arbor 3 and the other end fixed to a cross-rod 2" connecting the supports 2 and 2', 5 a key for winding the spring, 6 a ratchet wheel fixed to the arbor, 7 a gear wheel loose on the arbor, 8 a pawl pivotally connected with the gear wheel and engaging the teeth of the ratchet wheel, and 9 a spring bearing on the pawl. The gear wheel 7 meshes with a second gear wheel 10 fixed to a short shaft 49 11 which is mounted to rotate in the support 2 and another upright support 12. The gear 10 is in mesh with a pinion 13 fixed to a shaft 14 which has one end journaled in the support 2 and the other end journaled 50 in the upright support 15. Fixed to the shaft 14 is an escapement wheel 16 having a plurality of equally-spaced teeth 17, and a switch operating disk 18 also having a plurality of equally-spaced projections 19 corresponding in number to the teeth 17.

Cooperating with the teeth of the escapement wheel 16 are two detents 20 and 21, arranged on opposite sides of the escapement wheel. The detent 20 is formed on a long arm 22 which projects at right angles to the axis of the wheel, with a portion thereof lying in close proximity to the wheel, that portion being arched as indicated at 22' to avoid the shaft 14. The detent 21 is adjustably connected to the arm 22 and to that end is formed on a separate plate 23 which has lateral flanges 24 on its upper and lower edges to embrace the arm 22 and also has a slotted opening 25 through which passes a screw 26 secured to the arm 22 so as to slidably connect the same with the arm. The end of the arm 22 is bent to form a laterally projecting ear 27 and the outer end of the plate 23 is bent to form a laterally projecting ear 28 parallel with the ear 27. These ears 75 have aligned openings to receive an adjusting screw 29, the opening in the ear 28 being unthreaded and the opening in the ear 27 being threaded. The ear 28 also has a threaded opening to receive an adjusting screw 30 the end of which bears against the ear 27. By turning the screw 29 the plate 23 and its detent 21 may be slid on the arm 22 in the direction of the escapement wheel while by turning the screw 30 the plate and its detent are moved in the opposite direction away from the escapement wheel.

The other end of the arm 22 is pivotally connected to one arm 31 of a bell crank lever pivoted at 32 to a bracket 34 on the base 1. The other arm 33 of this bell crank lever is pivotally connected to a yoke 34', connected to one member 35 of a two-part rod, the other member 36 of which is connected to one wall of a thermostat 37 of the bellows type, the other wall being supported by the bracket 38. The two members 35 and 36 of the rod and the yoke are adjustably connected together so that the connection can be lengthened or shortened and to this end the member 35 is shown as having a reduced threaded stem 39 threaded into the member 36, and the yoke has a threaded stem 40 threaded in the member 35. The stems are oppositely threaded so that by turning the member 35 the connection may be lengthened or shortened, which, through the bell crank lever and arm 22, serves to adjust the detent 20 with relation to the teeth 17 of the escapement wheel.

The necessary movement of the arm 22 under the action of the thermostat is permitted by pivotally supporting that end opposite the bell crank lever, and to that end the arm has attached thereto an arm 41 by a screw 42, the arm 41 being pivotally supported by a bracket 43 secured to the base. The screw 42 passes through the slotted opening 25 to permit of the adjustment of the detent carrying plate 23.

In operation the mechanism is installed at any suitable point where it is desired to regulate temperature, such for instance as on an incubator for chickens, in which case the heat responsive element would be located in the incubating chamber. As the walls of the bellows contract or expand in response to the temperature, the bell crank lever is rocked and the arm 22 thereby moved in a direction substantially at right-angles to the axis of the escapement wheel. This movement causes one of the detents to release the escapement wheel and the other detent to be projected in the path of one of the teeth of the escapement wheel to again arrest the wheel. By adjusting the detents in the manner described it is possible to release the escapement wheel by a change in temperature of but a fraction of a degree if it is desired to maintain a substantially even temperature, as is the practice in incubation. When the escapement wheel is released it permits a partial rotation of the cam disk 18 so as to cause the cam projections thereon to either open the switch by contacting the pivoted member of the switch, as shown in Figs. 3 and 4, or permit the switch to close by freeing the pivoted member of the switch as indicated in Fig. 2.

The switch which I employ consists of a stationary contact member 44, supported on the base, and a movable contact member 45 supported on one end of a lever 46, the other end of which stands in the path of movement of the cam projections on the disk 18. The lever 46 has ears 47 which are pivotally connected to the ears of a supporting bracket 48 connected with the base 1. The arrangement is such that when the escapement wheel is released by the detent 21, one of the cam projections on the disk 18 will strike the lever 46 and separate the contacts 44 and 45, as shown in Fig. 3 and Fig. 4, while when the escapement wheel is released by the detent 20 the movement of the disk 18 is such that the next succeeding cam tooth will be removed from the end of the lever 46, as shown in Fig. 2, so as to permit the lever to swing by gravity and by the aid of a spring 49, to close the contacts.

Having thus described my invention, I claim:

1. In an electric switch, a switch operat-

ing member, a motor for operating same, a toothed escapement wheel and two detents 65 for same to release and arrest said motor, and a temperature responsive element for controlling said detents.

2. In an electric switch, a switch operating member, a motor for operating same, 70 a toothed escapement wheel and two detents for same to release and arrest said motor, a temperature responsive element for controlling said detents, and means for adjusting the detents relatively to the teeth of said 75 wheel.

3. In an electric switch, a switch operating member, a motor for operating same, a toothed escapement wheel rotated by the motor, a movable support arranged adjacent 80 said wheel, two detents carried by said support and cooperating with the teeth of said escapement wheel to release and arrest said motor, and a temperature responsive element connected with said movable support. 85

4. In an electric switch, a switch operating member, a motor for operating same, a toothed escapement wheel rotated by the motor, a movable support arranged adjacent 90 said wheel, two detents carried by said supports and cooperating with the teeth of said escapement wheel to release and arrest said motor, a temperature responsive element connected with said movable support, and means for adjusting said detents relatively 95 to the teeth of said wheel.

5. In an electric switch, a switch operating member, a motor for operating same, a toothed wheel rotated by said motor, a supporting arm movably mounted adjacent said wheel, a detent adjustably carried by said arm, a second detent fixedly carried by said arm, a temperature responsive element, and an adjustable connection between said element and said arm. 100

6. In an electric switch, a switch operating member, a motor for operating same, a toothed wheel rotated by said motor, a support movably mounted adjacent said wheel, a pair of detents carried by said support 110 and cooperating with the teeth of said wheel, a bell crank lever to one arm of which said support is connected, and a temperature responsive element connected to the other arm of said bell crank lever. 115

7. In an electric switch, a switch operating member, a motor for operating same, a toothed member movable with the motor, and a pair of detents arranged for simultaneous movement alternately into and out of the path of the teeth of said member, and a temperature responsive element for moving said detents. 120

In testimony whereof, I have hereunto set my hand this 3rd day of June, 1926.

JOHN PFEIFER.
